DESIGN FOR A COSMETIC BOX

Adam Baker Barnhart, New York, N. Y., assignor to Jacqueline Cochran, doing business as J. C.
Laboratories, Roselle, N. J.

Application August 9, 1937, Serial No. 70,946

Term of patent 14 years

To all whom it may concern:

Be it known that I, Adam Baker Barnhart, residing at New York, in the county of New York and State of New York, have invented a new, original, and ornamental Design for a Cosmetic Box, of which the following is a specification, reference being had to the accompanying drawing, forming part thereof.

In my design the upper or lid portion has a color and texture contrasting with that of the lower or container portion.

I claim:

The ornamental design for a cosmetic box, as shown, and described.

ADAM BAKER BARNHART.
